GIDEON BANTZ, OF FREDERICK, MARYLAND.

Letters Patent No. 86,803, dated February 9, 1869.

IMPROVED APPARATUS FOR EXTRACTING ESSENCES, &c.

The Schedule referred to in these Letters Patent and making part of the same.

To all whom it may concern:

Be it known that I, GIDEON BANTZ, of the city and county of Frederick, and State of Maryland, have invented a new and improved Apparatus for Extracting Essences, and for other purposes; and I do hereby declare that the following is a full, clear, and exact description of the construction and operation of the same, reference being had to the accompanying drawings, making a part of this specification, in which—

Figure 1 is a longitudinal vertical section through line *x* *x* of fig. 2.

Figure 2 is a plan.

The object of this invention is to provide an apparatus by which essences can be extracted more perfectly and expeditiously than heretofore, and which shall necessitate the incurring of but little expense in its construction and practical operation.

The apparatus thus constructed is of such a form and character that it may be conveniently employed for many other purposes.

The main principle involved in my improved apparatus is the peculiar manner of applying the boiling water to the materials which are to be subjected to its operation, such materials not only lying in a vessel of boiling water, but at the same time being subjected to the powerful action of several streams of water, which, elevated at the sides of the apparatus through the action of the heat and the steam, are thrown inward toward the centre of the vessel with great force.

In this manner a constant current of boiling water is maintained in the vessel, the fluid passing up at its sides and being thrown inward from around its top, thence flowing downward and outward to its sides again, where it is again elevated and dashed in toward the centre of the vessel.

The action of the boiling water, when thus dashed upon the materials with considerable force, and when accompanied by the action of atmospheric air, which is carried down by the jets into the mass of water and among the materials to be acted on, is much more energetic and thorough than when applied in the usual way.

In the drawings, the red lines indicate a boiler in which the apparatus is to be used. The black lines indicate the apparatus itself.

A indicates a plate, of sheet-metal, or other suitable material, to the upper side of which are attached several vertical tapering tubes, B B, which support a continuous horizontal tube, C, the latter being provided with a series of openings, c c, around its inner wall, and the whole being so constructed and connected that fluids can pass into the tubes B B from the under side of plate A, thence into pipe C, and thence, through the openings c c, into the space enclosed by pipe C, falling back upon the upper side of plate A.

Plate A is also provided with a circular rim, or flange, D, around its perimeter, and with a flange, E, smaller

in size, around its centre, both flanges extending downward. The apparatus rests on the outer flange, which sits on the bottom of the enclosing boiler.

When in this position, the inner flange does not come quite down to the bottom of the boiler, and the fluid can pass easily under it from the space F, enclosed by the inner flange, to the space G, enclosed between the two flanges.

The lower ends of the pipes B B project through the plate A, and to a short distance below it, as seen at b b.

Another flange, H, is attached to plate A, on its upper side, being in dimensions about midway between flange D and flange E, and being covered by a foraminated plate, h, and enclosing a central space, J.

Plate A is provided with several openings, I I I, inside of the flange E, and communicating between the spaces F and J.

Each opening communicates with space F through a short tube, i, which, being attached to the under side of plate A, so as to surround the openings I, extends about half way to the bottom of space F.

This constitutes the apparatus as complete and ready for use.

Its operation is as follows: It is placed within the boiler, in the manner represented in fig. 1, and, the latter being partially filled with water, is subjected to a lively heat. The materials to be subjected to its operation are placed upon the foraminous cover h. As soon as the water begins to boil, the steam in space G, above the lower end b of the vertical pipes, forces the boiling fluid up through the pipes into the tube C, and thence through the openings c c, driving it with great force upon and against the material below. Thence the water passes down through plate h and tubes i i, and under flange E to space G, whence it started.

This apparatus will operate with considerable success without the parts b, E, and i, as I have satisfied myself by experiment, but the full perfection of the instrument absolutely requires these parts, in order to afford a steam-space above the water, under plate A, in which the steam generated under the plate shall collect, so as to force the water up through the pipes and dash it upon the materials in a lively and effective manner.

Without the steam-spaces, the circulation of the fluids will take place, but in a slow and uncertain manner, and never except when subjected to a very high heat.

With the steam-spaces, as above described, the circulation is rapid and uniform, and the action of the apparatus in every way most efficient and successful.

I wish it to be distinctly understood that I do not claim any of the many washing-machines and dyeing-apparatus, which resemble my apparatus for extracting essences; but having thus described my invention,

What I claim as new, and desire to secure by Letters Patent, is—

1. The arrangement of flanges D and E with plate A, pipes B B, and projections b b, so as to form a steam-space above the water between flanges D and E, and above the lower end of the pipes, in the manner above described.

2. The arrangement of pipes i i, plate A, and flange

E, so as to form a second steam-space within the space F, in the manner described.

3. The arrangement of the perforated pipe C upon the top of the vertical pipes B B, in the manner described.
